US00D977486S

(12) **United States Design Patent** (10) **Patent No.:** **US D977,486 S**
(45) **Date of Patent:** **** Feb. 7, 2023**

(54) **TABLET KEYBOARD CASE**

(71) Applicant: **Qiao Dong**, Shenzhen (CN)

(72) Inventors: **Shanmian Wang**, Shenzhen (CN);
Qiao Dong, Shenzhen (CN)

(73) Assignee: **Qiao Dong**, Shenzhen (CN)

(**) Term: **15 Years**

(21) Appl. No.: **29/840,872**

(22) Filed: **Jun. 1, 2022**

(30) **Foreign Application Priority Data**

Feb. 14, 2022 (CN) 202230071526.4

(51) **LOC (14) Cl.** **14-02**

(52) **U.S. Cl.**

USPC **D14/440**

(58) **Field of Classification Search**

USPC D14/250, 440, 432, 447
CPC ... H04B 1/3888; B32B 38/1841; B32B 37/26;

G06F 1/166; G06F 1/1667

(57) **CLAIM**

The ornamental design for a tablet keyboard case, as shown and described.

DESCRIPTION

FIG. 1 is a perspective view of a tablet keyboard case, showing our new design;

FIG. 2 is another perspective view thereof;

FIG. 3 is a perspective view of the design in a closed status;

FIG. 4 is another perspective view thereof;

FIG. 5 is front view of the design shown in FIG. 1;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

1 Claim, 10 Drawing Sheets
